UNITED STATES PATENT OFFICE.

HARRY DANIEL LINDENMUTH, OF FLEMING, PENNSYLVANIA.

VALVE LIFTER.

Application filed February 1, 1922. Serial No. 533,432.

To all whom it may concern:

Be it known that I, HARRY D. LINDENMUTH, a citizen of the United States, residing at Fleming, in the county of Center and 5 State of Pennsylvania, have invented a new and useful Valve Lifter, of which the following is a specification.

This invention relates to valve spring compressors, the primary object of the invention 10 being to provide a valve spring compressor for use in connection with valve springs of various lengths.

Another object of the invention is to provide means to facilitate the application of 15 the lifter under the washer supported at the base of a valve spring.

A still further object of the invention is the provision of means for locking the valve spring compressor in its positions of adjustment, permitting the operator to have unrestricted use of his hands to accomplish the removal of the valve.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawing:

Figure 1 is an elevational view of a valve 35 spring compressor constructed in accordance with the present invention.

Figure 2 is an elevational view of the same.

Figure 3 is a sectional view taken on line 40 3-3 of Figure 2.

Figure 4 is an elevational view of the lower jaw of the spring compressor.

Referring to the drawing in detail, the device embodies a lower arm 5 and an upper 45 arm 6, each arm being formed with an extension 7 through which the arms may be pivotally connected.

Formed at the outer end of the arm 5 is a jaw 8, which is constructed to engage a 50 shoulder 9 formed at the base of the valve spring opening of an engine valve, as clearly shown by Figure 1 of the drawing.

The jaw 8 is bifurcated so that the same 55 may be slid into position around a valve stem, which in the present showing is indicated at 10, the valve stem being provided

with a suitable opening to accommodate the pin 11 employed for supporting the lower extremity of a valve spring.

The upper arm 6 has a curved extremity 60 12 forming one section of the upper jaw, the opposite section of the jaw being indicated at 13 and pivotally connected to the arm 14 carried by the jaw 12. This arm 14 extends laterally from the jaw 12 and is formed 65 with a plurality of openings 15 disposed in spaced relation with each other, to accommodate the pin 16 which passes through an opening in the jaw section 13, permitting the jaw 13 to be adjusted with respect to the stationary section 12 of the jaw.

As clearly shown by Figure 3 of the drawing, each of the sections 12 and 13 is curved transversely of its width to fit around a valve head, so that when the jaw sections are 70 positioned over a valve, the jaw sections will be held thereon, and restricted from movement. A rearwardly extending arm 17 forms a part of the jaw section 13 and is formed with a relatively flat portion 18 to 75 be engaged by the hand of the operator when it is desired to open the jaw sections to apply the tool. A coiled spring indicated at 19 is disposed between the arms 6 and rearwardly extending portions 17 of the jaw 80 section 18, for normally urging the jaw sections towards each other in gripping relation with each other.

Carried at the inner end of the arm 5 is a pivoted rod 20 formed with a threaded portion 21 to receive the winged nut 22. The arm 6 is formed with a notched portion 23 disposed in one end thereof, which notched portion is designed to accommodate the rod 20, providing means to secure the arms 5 and 6 against movement, when the same have been applied to a valve. In order that the rod 20 will be restricted from moving out of the notched portion of the arm 6, the extreme inner end of the arm is extended upwardly as at 23, providing stops or abutments to be engaged by the winged nut 22, when the same has been properly positioned.

In the use of the tool, the jaw 8 is positioned on the shoulder 9 directly under the pin 11, and the jaw sections 12 and 13 are moved to grip the washer supported under the valve spring. With the jaws in this position, the handle portions 5 and 6 are moved towards each other, compressing the valve spring contacting with the wash-

er to relieve the pin 11 of the tension of the spring.

It follows that the rod 20 is now moved to lock the arms 5 and 6 against movement.

Having thus described the invention what is claimed as new is:—

1. In a valve spring compressor, opposed arms pivotally connected, one of said arms having a bifurcated extremity to be positioned over a valve stem, one end of the opposed arm being curved, a jaw section cooperating with the curved end to grip a valve washer, said jaw section having pivotal connection with the curved end and having a rearwardly extended arm adapted to lie in spaced relation with the second mentioned arm to permit the pivoted jaw section to move with respect to the curved end of the second mentioned arm, and resilient means for normally urging the jaw section to its active position.
2. In a valve lifter, an upper arm and a

lower arm pivotally connected, the lower arm having a bifurcated end to fit around a valve stem, the upper arm having a curved end forming a jaw, a laterally extending member formed on the upper arm and having spaced openings, a pivoted jaw section cooperating with the jaw of the upper arm, means for pivotally connecting the jaw section to the laterally extending member, said pivoted jaw section having a rearwardly and outwardly extended portion lying in spaced relation with the upper arm, and means for normally urging the jaw section towards the jaw of the upper arm.

In testimony that I claim the foregoing as my own, I have hereto affixed my signature in the presence of two witnesses.

HARRY DANIEL LINDENMUTH.
